We claim the ornamental design for the sprayer engine package enclosure, as shown and described.

DESCRIPTION

FIG. 1 is a top left perspective view of the sprayer engine package enclosure showing our new design;

FIG. 2 is a top view of the sprayer engine enclosure;

FIG. 3 is a left side view of the sprayer engine enclosure;

FIG. 4 is a front view of the sprayer engine enclosure;

FIG. 5 is a right side view of the sprayer engine enclosure;

FIG. 6 is a rear view of the sprayer engine enclosure; and,

FIG. 7 is a bottom view of the sprayer engine enclosure.

The broken line showing of FIGS. 1-7 is included for purpose of illustrating portions of the sprayer engine package enclosure and forms no part of the claimed design.
